UNITED STATES PATENT OFFICE.

JOSEPH F. HANCOCK, OF OTTUMWA, IOWA.

IMPROVEMENT IN CAR-COUPINGS.

Specification forming part of Letters Patent No. **147,637**, dated February 17, 1874; application filed May 24, 1873.

To all whom it may concern:

Be it known that I, J. F. HANCOCK, of Ottumwa, in the county of Wapello and in the State of Iowa, have invented certain new and useful Improvements in Car-Coupling; and do hereby declare that the following is a full, clear, and exact description thereof, reference being had to the accompanying drawings and to the letters of reference marked thereon, making a part of this specification.

The nature of my invention consists in the construction and arrangement of a car-coupling, as will be hereinafter more fully set forth.

In order to enable others skilled in the art to which my invention appertains to make and use the same, I will now proceed to describe its construction and operation, referring to the annexed drawing, in which—

Figure 1 is a plan view of my car-coupling. Fig. 2 is a horizontal section, Fig. 3 a side view, and Fig. 4 a front view, of one of the draw-heads.

A A represent two draw-heads, constructed in any suitable manner, and each provided at its front or outer end with a flange, *a*, projecting outward on each side, as shown in Figs. 1 and 2. In each draw-head A are pivoted two draw-bars, B B, projecting forward (one on each side) beyond the front or outer end of the head. Through the inner or rear ends of the draw-bars B B passes a rod, *b*, with a spiral spring, *d*, around the same, to operate on the draw-bars so as to throw their outer or front ends inward. In the inner side of the outer end of each draw-bar B is cut a square notch, *i*, to grasp the flanges *a a* of two opposite draw-heads.

When the cars are coupled, the draw-bars of each car catch on the flange of the coupling

on the opposite car, and the spring *d* in rear holds the draw-bars over the flange.

It will be seen, by reference to Figs. 1 and 2, that the back shoulder of the notch *i* presses immediately behind the flange *a* of the coupling, and thus serves to ease the pressure on the pins which pivot the draw-bars, and prevent them from breaking too easily.

In each draw-head A, between the draw-bars B B, is placed a cam, C, on a vertical shaft, *f*, by means of which the front ends of the draw-bars are spread apart to uncouple the cars.

The front ends of the draw-heads are provided with one or more apertures, *e*, and a pin, *h*, so that the ordinary pin-and-link coupling can be used.

If both draw-bars on one coupling should break and those on the other remain unbroken, the cars will, nevertheless, move along without separating; or, if one draw-bar on each car breaks, one of the others can be changed, so as to make a complete coupling on one draw-head; or, if all should become broken, the ordinary link can be used.

Having thus fully described my invention, what I claim as new, and desire to secure by Letters Patent, is—

The draw-heads A A, provided with flanges *a a*, in combination with the draw-bars B B and the springs which operate the same, as and for the purpose set forth.

In testimony that I claim the foregoing I have hereunto set my hand this 15th day of May, 1873.

J. F. HANCOCK.
